UNITED STATES PATENT OFFICE

145,083

DESIGN FOR A SURFBOARD

Levi S. Howland, Long Beach, Calif.

Application February 25, 1944, Serial No. 112,713

Term of patent 14 years

(Cl. D71—1)

To all whom it may concern:

Be it known that I, Levi S. Howland, a citizen of the United States of America, residing at Long Beach, in the county of Los Angeles, State of California, have invented a new, original, and ornamental Design for a Surfboard, of which the following is a specification, reference being had to the accompanying drawings, forming a part thereof, in which:

Fig. 1 is a top plan view of a surfboard, showing my design;

Fig. 2 is a side elevational view thereof;

Fig. 3 is an enlarged front elevational view thereof;

Figs. 4, 5, and 6 are enlarged transverse sectional views thereof, taken respectively through 4—4, 5—5, and 6—6 of Fig. 2; and,

Fig. 7 is a longitudinal sectional view taken through 7—7 of Fig. 1.

I claim:

The ornamental design for a surfboard, substantially as shown.

LEVI S. HOWLAND.
